UNITED STATES PATENT OFFICE.

JOHN H. BLAKE, OF SALT LAKE CITY, UTAH TERRITORY.

RULER.

SPECIFICATION forming part of Letters Patent No. 392,846, dated November 13, 1888.

Application filed May 2, 1888. Serial No. 272,594. (No model.)

To all whom it may concern:

Be it known that I, JOHN H. BLAKE, a subject of the Queen of Great Britain, residing in Salt Lake City, in the Territory of Utah, have 5 invented certain Improvements in Rulers, of which the following is a specification.

My invention relates to that class of rulers, for use in the counting-room or on the desk, in which a cylindrical ruler is combined with 10 a flat beveled ruler.

My invention will be fully described hereinafter, and its novel features carefully defined in the claim.

In the drawings, whereon my invention is 15 illustrated, Figure 1 is a plan of my ruler. Fig. 2 is an end elevation, and Fig. 3 is a cross-section, of same.

A is a simple cylindrical ruler, of any suitable material, and B is a flat ruler with a beveled and graduated edge, *b*, which may be provided with a metal strip, *b'*. The flat ruler B will be of about the same length as the cylindrical ruler A. The two rulers are connected by two links, C C, pivoted to the ends of the 25 ruler A at its axis, so that the ruler may roll or turn on said pivots as journals, and pivoted at their other ends to the respective ends of the flat ruler B at about the middle point of the ends, so that said ruler may turn or rotate 30 on said pivots, and thus enable either edge of the ruler B to be turned outward, or from the cylindrical ruler A. This pivotal and rotary

mounting of the flat ruler enables either edge of it to be conveniently used as a ruler or for measuring.

In parallel rulers of this class, when the cylindrical part or element is used merely as a roller or wheel, the flat ruler has not been pivoted rotatively, and it has been placed so close to the cylindrical element that its inner edge, 40 or that adjacent to the cylinder, could not be utilized. In my construction either edge of the flat ruler may be used, and this ruler may be used with either side up. Indeed, the flat ruler may be utilized as fully as if it were not 45 connected with the cylindrical ruler, while it serves also to hold and steady the latter when it is in use.

Having thus described my invention, I claim—

As an improved article of manufacture, a compound ruler consisting of a cylindrical ruler, A, and a flat ruler, B, pivotally connected at their ends by two links, C C, said rulers being both free to rotate on their respective pivotal axes, as and for the purposes set forth.

In witness whereof I have hereunto signed my name in the presence of two subscribing witnesses.

JOHN H. BLAKE.
